UNITED STATES PATENT OFFICE

113,516

DESIGN FOR A TOOTHPICK

Philomene G. McAlear, Chicago, Ill.

Application August 8, 1938, Serial No. 79,183

Term of patent 14 years

To all whom it may concern:

Be it known that I, Philomene G. McAlear, a citizen of the United States and residing at Chicago, in the county of Cook, and State of Illinois, have invented a new, original, and ornamental Design for Toothpicks, of which the following is a specification, reference being had to the accompanying drawing, forming a part thereof.

Fig. 1 is a side elevational view of the toothpick showing my new design;

Fig. 2 is a view similar to Fig. 1, showing the other side of the toothpick;

Fig. 3 is a top plan view thereof.

The characteristic features of my design reside in a toothpick of the configuration shown having at one end thereof letters arranged on opposite sides thereof.

I claim:

The ornamental design for a toothpick, substantially as shown and described.

PHILOMENE G. MCLEAR.
